(57) **CLAIM**

The ornamental design for an automated teller machine, as shown and described.

DESCRIPTION

FIG. 1 is a perspective view of an automated teller machine, showing our new design.

FIG. 2 is a front view of the automated teller machine of FIG. 1.

FIG. 3 is a rear view of the automated teller machine of FIG. 1.

FIG. 4 is a left side view of the automated teller machine of FIG. 1.

FIG. 5 is a right side view of the automated teller machine of FIG. 1.

FIG. 6 is a top view of the automated teller machine of FIG. 1; and,

FIG. 7 is a bottom view of the automated teller machine of FIG. 1.

Portions of the disclosure shown in broken lines form no part of the claimed design.
